UNITED STATES PATENT OFFICE.

JAMES GREER, OF EAST ORANGE, NEW JERSEY, ASSIGNOR TO HIMSELF, AND MAURICE W. COLLINS, OF PHILADELPHIA, PENNSYLVANIA.

TANK-CAR.

1,163,144.

Specification of Letters Patent.

Patented Dec. 7, 1915.

Application filed March 19, 1915. Serial No. 15,652.

To all whom it may concern:

Be it known that I, JAMES GREER, a citizen of the United States, residing at East Orange, in the county of Essex and State of New Jersey, have invented a certain new and useful Improvement in Tank-Cars, of which the following is a specification.

The invention relates to railway tank cars in which oils or other liquids are transported in bulk, and more particularly to the valved outlet or delivery nozzle with which such cars are equipped.

In the usual type of tank-car the nozzle is on the under face of the tank and is controlled by a loose vertically movable valve operated by a valve-rod extending upwardly through the tank and its contents to a handle located in a dome on the upper face of the tank. The lower end of the nozzle is screw-threaded and receives a cap screwed thereon to insure against leakage. It frequently happens that the valve is not properly seated, or by reason of accident or carelessness, is entirely disconnected from its seat and the contents is retained solely by the cap which permits the car to be transported with no indication that it is not in good order; but on removing the cap in making the required connections in emptying at the point of destination, the contents gushes out with such force that it is impossible to again replace the cap, and the result is a great waste of the contained liquid with the added danger of fire if the contents be oil which is the liquid mainly transported in cars of this character.

The object of the invention is to provide the nozzle with an indicating means by which the condition of the valve may be ascertained before the cap is removed, and to provide a simple, inexpensive and efficient form of indicator adapted to withstand successfully the rough usage to which mechanism of this class is subjected in service.

The invention consists in certain novel features and details of construction and arrangement by which the above objects are attained, to be hereinafter described and claimed.

The accompanying drawings form a part of this specification and show the invention as it has been carried out in practice.

Figure 1 is a side elevation, partly in vertical section, showing a portion of a tank-car equipped with the invention and in the

closed condition. The remaining figures are on a larger scale and show the cap and its indicating means alone. Fig. 2 is a side elevation with the indicator fully open. Fig. 3 is a transverse vertical section with the indicator closed. Fig. 4 is a similar section, corresponding to Fig. 2. Fig. 5 is a plan view of the same parts. Fig. 6 is a horizontal section taken on the line 6—6 in Fig. 4.

Similar letters of reference indicate the same parts in all the figures.

A is the tank, of cylindrical form disposed horizontally on a car-frame and trucks, not shown, and A¹ is the dome on the upper face of the tank, having a removable cover A². On the lower face is the outlet pipe or delivery nozzle B containing a valve B¹ matching to a conical seat at B² on the upper end of the nozzle and having guide-wings B³ within the latter serving to guide the valve in its vertical movements. C is a valve-rod joined to the upper end of the valve by a pivot connection at C¹ and extending vertically through the tank into the dome, passing through a bracket C² secured to the inner face of the dome and equipped, in the form shown, with a handle C³ by which the valve may be lifted from its seat in opposition to the force of a helical spring C⁴ inclosing the upper portion of the rod and abutting at one end against a collar C⁵ thereon and at the upper end against the bracket C². All these parts may be understood to be of the usual or any approved construction.

The nozzle B is screw-threaded exteriorly at the lower end and receives a cap D screwed thereon to prevent the oil or other liquid escaping through a leaky valve from spraying along the right-of-way while the car is in transit. The cap has a squared or hexagonal boss D¹ on the lower face by which it may be strongly screwed home by the application of a suitable wrench to compress an annular gasket D² interposed between the lower end of the nozzle and interior face of the cap and thus make a tight joint. The cap is ordinarily a simple closed cup and is connected to the tank or fixed portion of the frame by a chain D³ so joined as to permit the cap to be applied or removed without danger of displacement or loss when separated.

The essential feature of the invention is in

providing an orifice in the nozzle, or preferably in the cap, and providing a controlling means for such orifice, whereby the communication with the interior of the nozzle 5 may be gradually established and the condition of the valve thus ascertained. If there be no escape of liquid, the valve is obviously properly seated and the cap may be removed safely to make the usual tank connection 10 through which the car is emptied; or, if the flow be slight, it indicates a leaky or defective valve seating, but may not prevent making the tank connections; but if the liquid flows with great force it is evident 15 the valve is not holding and the cap must not be removed for the reason that it would be impossible to replace it and stop the flow.

As the invention has been carried out the indicator comprises a screwthreaded plug 20 F of less diameter than the interior of the nozzle, matching to and received in an orifice correspondingly drilled and tapped axially through the boss D¹ of the cap, and having its upper end hollow or deeply recessed as at f and provided with vertically located open slots or ports f¹ at the bottom of such recess. A squared or hexagonal head F¹ at the lower end affords means for turning it and thus raising or lowering it 25 relatively to the cap when the latter is in place on the nozzle. The plug is preferably tapered slightly so as to make a liquid-tight joint when forcibly screwed home and to turn easily when partly lowered. By thus 30 slackening the plug and slowly lowering it the ports f¹ f¹ are gradually uncovered below the under face of the cap and communication thus established between the interior and exterior of the nozzle, and liquid in the 35 nozzle below the valve may thus escape, the flow being readily controlled by varying the position of the plug and correspondingly varying the exposed area of the ports.

To prevent complete separation of the 40 plug and consequent danger of loss, a narrow lock-nut or collar F² is screwed upon the upper end after its insertion in the cap. The collar is held against unscrewing by one or more rivets F³ extending through the 45 collar and the annular wall at that end of the plug. By thus preventing the removal of the plug all danger of cross-threading by imperfect replacement is also eliminated.

The operation is as follows:—Assuming 50 the tank to be full and placed for unloading, the operator unscrews the plug sufficiently to bring the ports below the cap and thus ascertain whether the valve is unseated or defective. This will be indicated by the 55 leakage of liquid through the ports. Should there be no leakage the cap may be safely removed, with the plug, and the usual tank connections made with the nozzle. Should the indicator show an abnormal leakage the 60 operator may endeavor by manipulating the

valve-rod C through the dome cover to close the valve, or if the latter is out of place to re-seat it; if successful the flow through the indicator will cease and the tank connections may be made. Should such efforts prove unsuccessful it will be dangerous to attempt to empty the tank and the indicator may be again screwed home and the tank returned to the consignor with contents intact.

Modifications may be made within wide 75 limits without departing from the invention. Other means may be employed to control the orifice and serve to show the condition of the valve. The plug form is preferred on account of its efficiency and extreme simplicity together with its ability to endure rough handling without serious damage.

I claim:—

1. In a tank car having a delivery nozzle 85 and a valve fitted to a seat on the upper end of said nozzle, said valve controlling the flow of liquid from the tank to the nozzle, a cap to said nozzle normally closing the outlet thereof and means adjustable in the cap and 90 extending within the nozzle and movable lengthwise thereof to provide an auxiliary outlet from the nozzle.

2. In a tank car having a delivery nozzle 95 and a valve controlling the flow of liquid from the tank to said nozzle, means normally controlling the outlet from said nozzle, and means independent of the first-named means adjustable lengthwise of the nozzle and providing an auxiliary outlet 100 from the nozzle to permit a flow of the liquid from the nozzle through said first-mentioned means.

3. In a tank-car having a delivery nozzle and a valve controlling the flow of liquid 105 from said tank to said nozzle, a cap for the latter normally closing the outlet thereof, a plug in said cap having an orifice communicating with the interior of said nozzle below said valve and forming an auxiliary 110 outlet from the nozzle, and means for operating such plug.

4. In a tank-car having a delivery nozzle and a valve controlling the flow of liquid from said tank to said nozzle, a cap for the 115 latter normally closing the outlet thereof, a plug in said cap having an orifice communicating with the interior of said nozzle below said valve and forming an auxiliary outlet from the nozzle, said plug controlling the 120 flow of liquid from the interior of the nozzle.

5. In a tank-car having a delivery nozzle and a valve controlling the flow of liquid from said tank to said nozzle, a cap for the latter normally closing the outlet thereof, a 125 plug in said cap having an orifice communicating with the interior of said nozzle below the valve, said plug controlling the flow of liquid from the interior of the nozzle, said plug having ports forming an auxiliary out- 130

let from the nozzle, and adapted to permit an adjustable flow of liquid from said nozzle.

6. In a tank-car having a delivery nozzle and a valve controlling the flow of liquid from said tank to said nozzle, a cap for the latter normally closing the outlet thereof, a plug in said cap having an orifice communicating with the interior of said nozzle below the valve, said plug controlling the flow of liquid from the interior of the nozzle, said plug having ports forming an auxiliary outlet from the nozzle, and adapted to permit an adjustable flow of liquid from said nozzle, and means for preventing withdrawal of the plug from the cap.

7. In a tank-car having a delivery nozzle and a valve controlling the flow of liquid from said tank to said nozzle, a closing cap

for the latter having an orifice therein 20 communicating with the interior of said nozzle below said valve, a screw-plug in such orifice, having a recess in its end and ports leading from said recess to the exterior of said plug within said nozzle, and a collar on 25 the inner end of said plug to prevent its disengagement from said cap, such ports and recess arranged to permit a variable flow of liquid from the interior of said nozzle by partially removing said plug. 30

In testimony that I claim the invention above set forth I affix my signature, in presence of two witnesses.

JAMES GREER.
